US0D1028700S

(12) **United States Design Patent** (10) **Patent No.:** **US D1,028,700 S**
(45) **Date of Patent:** **** May 28, 2024**

(54) **HELICAL PILE**

(71) Applicant: **Daiye Screw Pile LTD.**, Taipei (TW)

(72) Inventor: **Jen Te Yang**, Taipei (TW)

(73) Assignee: **Daiye Screw Pile Ltd.**, Taipei (TW)

(**) Term: **15 Years**

(21) Appl. No.: **29/839,731**

(22) Filed: **May 24, 2022**

(51) **LOC (14) Cl.** **08-08**

(52) **U.S. Cl.**

(57) **CLAIM**

The ornamental design for a helical pile, as shown and described.

DESCRIPTION

FIG. 1 is a perspective view of helical pile according to the present design;

FIG. 2 is a front view of the helical pile according to the present design;

FIG. 3 is a rear view of the helical pile according to the present design;

FIG. 4 is a top view of the helical pile according to the present design;

FIG. 5 is a bottom view of the helical pile according to the present design;

FIG. 6 is a right-side view of the helical pile according to the present design; and,

FIG. 7 is a left-side view of the helical pile according to the present design.

1 Claim, 7 Drawing Sheets
